UNITED STATES PATENT OFFICE

LUTHER C. CROWELL, OF NEW YORK, N. Y., ASSIGNOR, BY DIRECT AND MESNE ASSIGNMENTS, TO ROBERT HOE AND CHARLES W. CARPENTER, COPARTNERS UNDER THE FIRM-NAME OF R. HOE & COMPANY, OF NEW YORK, N. Y.

STAPLING-MACHINE.

No. 801,301.

Specification of Letters Patent.

Patented Oct. 10, 1905.

Application filed May 11, 1899. Serial No. 716,334.

To all whom it may concern:

Be it known that I, LUTHER C. CROWELL, a citizen of the United States, residing at New York city, county of Kings, and State of New York, have invented certain new and useful Improvements in Stapling-Machines, fully described and represented in the following specification and the accompanying drawings, forming a part of the same.

10 This invention relates to certain improvements in stapling mechanism of the kind employed for inserting staples in the folded product of high-speed printing-machines.

The mechanism which embodies the invention is more particularly intended for inserting staples in the corners of folded newspapers in order to prevent the fraudulent return of the papers to the publisher after the same have been sold to the customers and read 20 by them, the staple showing whether or not the paper has been opened.

The object of the invention is to provide a stapling mechanism which shall be adapted for use in printing-machines which produce 25 products of varying sizes. As is well known in the art, it is frequently desired to change the form of the output of a printing-machine by varying the number of pages which it contains, and the present invention is directed 30 toward enabling this to be done without extensive changes in the stapling mechanism. To this end the stapling mechanism is constructed so that it may be quickly adapted to changes in the output of the machine.

35 While the invention is adapted for the particular use above set forth, it is by no means to be restricted thereto, as it is capable of uses in many other relations.

The invention consists in certain constructions and in certain parts, improvements, and combinations, as will be hereinafter described, and fully pointed out in the claims hereunto appended.

In the accompanying drawings, forming a 45 part of this specification, and in which like reference characters indicate the same parts, Figure 1 is a view illustrating diagrammatically the folding mechanism of a printing-machine with the stapling mechanism in place therein 50 in its proper position with relation to the other parts of the machine. Fig. 2 is a plan view of

the stapling mechanism, the view being taken on a plane indicated by the line 2 2 in Fig. 1. Fig. 3 is an end view, on an enlarged scale, of the stapling mechanism, part of one of the 55 stapling-rolls being broken away to more clearly show the interior construction. Fig. 4 is a sectional view taken on the line 4 4 of Fig. 2, the parts being shown in the position they assume when the staple-forming mechanism is about to take the wire length. Fig. 5 is a similar view showing the parts in the position they assume as the staple is being clenched after insertion. Fig. 6 is a plan view showing the staple-forming rolls and the wire-feeding devices, a portion of the frame being shown in section and the horn being omitted. Fig. 7 is a sectional view taken on the line 7 7 of Fig. 6 looking in the direction of the arrow. Figs. 8 and 9 are sectional detail views 70 taken on the lines 8 and 9, respectively, of Fig. 4. Fig. 10 is a perspective view of the device for inturning the ends of the staple. Fig. 11 is a side view illustrating the gearing for operating the staple-feeding mechanism. 75 Fig. 12 is a front view showing a modification in which the stapling-rolls also operate as folding-rolls. Fig. 13 is a detail plan view, partly in section, showing the devices for controlling and feeding the wire. Fig. 14 is 80 a perspective view of a folded sheet with a staple inserted in its corner, and Fig. 15 is a sectional detail showing a series of plies of paper with the staple inserted therethrough and clenched. 85

In the embodiment of the invention which has been selected for illustration in connection with this application A A B B indicate the guiding and fold-laying rollers ordinarily used in connection with a longitudinal folder 90 of common construction. These guiding and fold-laying rollers might, however, equally well receive the product which it is desired to staple from any other source. C is a rotary carrier mounted on a shaft C' and provided with the usual folding-blades c, pins c', and cutting-blocks c'', and with this carrier coöperates another rotary carrier D, mounted on a shaft D', provided with a knife d and pins d'. In the form of the invention shown 95 in Fig. 1 a pair of fold-laying rolls E, mounted on suitable shafts, coöperates with the rotat- 100

ing carrier C, the whole forming a rotary folding mechanism of a well-known type, which may be used as a collecting mechanism when desired. The folded product passes 5 from the rolls E between a pair of pivoted guides F, which present it to a set of stapling-rolls carried on the shafts H I, which rolls after stapling it deliver it to a rotary fly S of well-known construction.

10 The rotary fly S is driven by a train of gears G (indicated by dotted lines in Fig. 1) from the rotary folding mechanism before described, and the arrangement of gearing is such that the fly-shaft is given one-quarter of a 15 revolution to each half-revolution of the carrier C. The stapling-roll shafts H I are driven from the fly-shaft by a train of gears g, (also indicated in dotted lines in Fig. 1,) the arrangement being such that these shafts are 20 given two revolutions for each quarter-turn of the fly-shaft. Inasmuch as each quarter-revolution of the fly-shaft delivers the folded paper, it will be seen that the stapling-rolls on the shafts H I must make one idle revolution—that is, one revolution during which no 25 staple is formed and driven.

The wire W, from which the staples are formed, is taken from any suitable source, as from a spool T, conveniently mounted in the 30 machine. The wire is led through a guide 20, (see Figs. 6 and 13,) which guide is preferably curved and provided with a groove or channel through which the wire passes. This guide preferably delivers the wire to a 35 pair of wire-feeding rolls 21 21, mounted on shafts 22 22. These shafts are preferably intergeared, so that one of them is driven from the other. One of the shafts 22 (herein shown as the lower one) is provided with a beveled 40 gear 23, (see Figs. 2 and 11,) which meshes with a beveled gear 24. This beveled gear 24 is mounted on a short shaft 25, which shaft is further provided with a gear 26. Beneath the shaft 25 is mounted a shaft 27, carrying 45 gears 28 and 28', and beneath the shaft 27 is mounted a shaft 29, on which is slidingly mounted, by means of a spline and set-screw or in any other convenient way, a pair of gears 30 30' and a gear 30''. The gear 30'' is 50 one of the gears of the train leading from the fly-shaft and serves to operate the shaft 29. The gears 26 and 28 have the same number of teeth, and the gears 28' and 30' have the same number of teeth; but the gear 30 has twice as 55 many teeth as the gear 28. When, as shown in Fig. 2, the gear 30 is in mesh with the gear 28, the shaft 27 and the shaft 25, which operates the wire-feeding-roll shaft, have a speed which is twice the speed of the shaft 29. By shifting the gears 30 30' to the right, 60 as shown in Fig. 11, so as to move the gear 30 out of mesh with the gear 28 and bring the gear 30' into mesh with the gear 28', the speed of the shaft 27 and the speed of the

shaft 25, with which it is geared, are reduced 65 one-half or to a speed equal to the shaft 29. In other words, when the gear 30 is in mesh with the gear 28 and these gears are operating to drive the wire-feeding-roll shaft and the wire-feeding rolls the wire is fed at twice 70 the speed at which it is fed when the gear 30' is in mesh with the gear 28' and these gears are operating to drive the wire-feeding rolls. Provision is thus made for changing the speed 75 of the wire-feeding devices to correspond with certain other adjustments, which will be hereinafter described.

The feeding-rolls 21 deliver the wire to a wire-presenting mechanism, the office of which is at proper times to place a length of wire 80 sufficient to form a staple in the path of the staple-forming devices. This presenting mechanism preferably consists of a block 32, having a forwardly-projecting portion 32', in which is formed a wire-receiving groove 33. 85 This wire-presenting block 32 preferably has secured to it in any convenient way, as by screws, a wire-guiding block 31, having a perforation 31'. This wire-guiding block is located between the presenting-block and the 90 wire-feeding rolls and serves to keep the wire under control at all times, and particularly during the movement of the presenting-block, hereinafter described, so that the wire may always be accurately fed to the wire-receiving 95 groove 33. Preferably the mouth of the perforation 31' will be flared so as to allow the block 31 to move without sharply bending the wire.

The block 32 has a movement toward and 100 away from the staple-forming mechanism so that it may at the proper time bring a length of wire into the path of said forming mechanism and at other times hold the wire away from it. While the presenting mechanism 105 may be operated in various ways so as to effect the movement desired this movement is preferably provided for by pivoting the block 32 by means of a stud 34, which works in a suitable bearing 35, to a bracket K, which is 110 suitably secured to the machine and carries certain parts of the stapling mechanism. The stud 34 has connected to it in any suitable manner an arm 36, which arm is preferably provided with a bowl operating in connection 115 with cam projections 37 on a cam-disk 38, which is carried by the fly-shaft L. The movement of the arm 36 is resisted and its bowl kept in contact with the cam by means of a spring 39, operating against an adjustable 120 collar 40' on a rod 41', which rod is pivoted to the arm 36 at one end and at its other end plays through the bent end of a bracket 42', which is suitably secured to the bracket K. The spring 39 has the end opposite to that 125 which bears upon the collar 40' bearing against the bent end of the bracket 42', and thus operates to hold the arm against the cam-disk 38

in an obvious manner. It is apparent that the wire-presenting block 32 by means of the devices just described will normally be held backward away from the stapling-roll and 5 that it will be rocked forward toward the roll whenever one of the cam projections 37 comes in contact with the bowl upon the end of the arm 36. Some of the cam projections 37, or 10 all of them, if it is thought desirable, may be separate from the cam-disk 38 and adjustable thereon, so as to be either in an operative or inoperative position. In the machine shown two of the cam projections 37 are thus made 15 adjustable. This adjustment may be accomplished in various ways. A convenient form of adjustment, however, is to pivot the cam projections 37 to the cam-disk 38, as shown, the pivot being marked 37^a. The projections are further provided with threaded pins 37^b, 20 which engage either one of two sets of holes in the cam-disk 38. When the pins 37^b are caused to engage the outer set of holes in the cam-disk 38, the cam projections are operative and when the said pins engage the inner 25 set of holes the cam projections are rendered inoperative.

The staple forming and inserting mechanism is of the rotary form and is carried on two shafts H and I, which are preferably inter- 30 geared and one of which carries a gear which forms one of the train leading to the fly-shaft. (See Fig. 2 and dotted lines in Fig. 1.) The staple forming and driving mechanism is mounted on the shaft I and is preferably carried 35 between two rolls 40 41. Each of these rolls serve to support one of the staple-forming blocks 42 43. Each of these blocks preferably has its outer face located in different planes, the rear portion of the block lying 40 above the front portion. This construction provides each of the blocks with a shoulder, the shoulders being numbered, respectively, 42^a and 43^a, and these blocks are further provided with grooves 42^b 43^b, which grooves extend 45 radially with respect to the axis of the shaft I, upon which the stapling-rolls are carried. The block 43 is also preferably provided with a cutting edge which coöperates with the edge of the guiding-block 31 to sever the wire. 50 When the wire-presenting block 32 has been rocked into its forward position, its projection 32', which is substantially equal to the space between the staple-forming blocks 42 43, will occupy such a position that the staple-forming blocks will pass on each side of it. At this time a length of wire which has been fed forward by the wire-feeding rolls will lie in the groove 33 of the block 32. As the 55 staple-forming rolls rotate the cutting edge of the block 43 will act, together with the block 31, to sever the wire, as above described. The shoulders 42^a 43^a will come in contact with the ends of the length of wire just after it is severed and the wire will be carried forward, rest-

ing upon the blocks 42 43 and against the 65 shoulders 42^a 43^a.

Coöperating with the staple-forming blocks 42 43 is the staple-forming anvil 44, which is secured to the bracket K in any desirable manner. This anvil is curved in form and is located over and lies for a part of its length in the space between the rolls 40, so that the blocks 42 43 will pass on each side of it. As these blocks carrying the length of wire travel 70 onward the wire will be forced by the anvil 75 down into the space between the blocks and into the grooves 42^b 43^b. The wire is thus bent up into U shape and the staple is formed.

In order that the ends of the staple-legs may be more readily inturned in the clenching operation, which takes place after they have been inserted into the paper, it is desirable to give them a slight inward turn or bend. In order to accomplish this, the anvil 44 is preferably provided upon its sides for a part of its length 80 with grooves 45 and also with plates 46, which are secured to the anvil by screws or in any suitable manner. The plates 46 have inwardly-turned cam projections 47, the arrangement and contour of these projections being clearly 85 shown in detail view in Fig. 10. As the wire length is carried forward by the blocks 42 43 and bent up into a staple the ends of its legs pass between the sides of the anvil and the curved cam projections of the plates 46 and 90 95 are bent by said projections into the grooves 45 in the manner clearly indicated by Fig. 8, the staple thus being given the form shown in the detail view in Fig. 9. The anvil 44 is preferably provided with a spring 48, which 100 overlies its outer side and projects somewhat beyond its extreme end into the space between its stapling-rolls. The purpose of the spring will be hereinafter stated.

Mounted between the staple-forming blocks 105 42 43 is a staple-driver 50. This staple-driver is preferably provided with shoulders 51, which partially embrace the blocks 42 43, and these blocks thus serve to guide the driver in its movement. The driver is also provided 110 with a transverse groove 52, in which the cross-bend of the staple is received. During the wire-receiving and staple-forming operations the staple-driver is retracted into the position shown in Fig. 4. After the staple is 115 completely formed and is brought by the rotation of the forming devices to the point where it meets the product into which it is to be inserted the driver must be given a forward movement in order to insert the staple. The 120 means for giving the driver this movement may be widely varied. They are, however, preferably constructed as follows:

Secured to the under side of the driver 50 by means of a pin-and-slot connection is an 125 arm 60. This arm 60 is carried upon a shaft 61, (see Fig. 6,) which shaft is located in and carried by the roll 41, before described. This

shaft 61 is a rock-shaft and has projecting from the end opposite to that which carries the arm 60 a crank-arm 62, carrying a bowl 63, which contacts with a stationary cam 64. 5 This stationary cam may be mounted in any suitable or convenient place, but is preferably mounted on the journal in which the shaft I of the roll 41 is mounted. The end of the arm 60 opposite to that which engages the 10 staple-driver 50 bears against the spring 65, which is located in a socket 66, carried on a bracket 67, mounted upon the roll 41. It is obvious that as the roll 41 rotates the bowl 63 will follow the contour of the cam 64, being 15 held thereagainst by means of the operation of the spring 65, and the driver will, by the eccentricity of the cam, be caused to reciprocate in and out to drive the staple at the proper time. The shaft H also carries two 20 rolls 70 71, which lie in the same planes as the rolls 40 41 of the shaft I. These rolls 70 71 have secured to them a clenching-plate 72, provided with a groove 73. The office of this clenching-plate and groove is to clench the end 25 of the staple and give it the form shown in Fig. 12.

The operation of the machine is as follows: The machine being adjusted, as shown in Fig. 1, the folded web from a longitudinal folder 30 or other suitable source passes between the rolls A and B to and between the carriers C D. One set of pins on the carrier C seizes the leading end of the web and carries it forward until the cutter on the carrier D 35 comes into coöperative relation with one of the cutting-blocks on the carrier C. At this time a sheet length is cut off and tucked down between the rollers E, from which it passes from the guides F to the stapling-rolls 40 41 and 70 71. The wire-feeding rolls 21, which in the machine described are shown as continuously - operating rolls, are in the meanwhile acting to feed forward a length of wire sufficient to form a staple, said length 45 passing through the curved guide 20 to these rolls and from them through the guide-block 31 into the groove 33 of the wire-presenting block 32. At the proper time one of the cam projections 37 on the cam 38 strikes the 50 roller on the arm 36 and lifts it, rocking the presenting-block 32 forward so that the length of wire which it carries will be in the path of the staple-forming blocks 42 43, which are carried upon the rolls 40 41 of the shaft I. 55 As these rolls rotate the forming-blocks 42 43 pass on each side of the projection of the presenting-block and remove the wire therefrom, the cutting edge of the block 43 operating to sever the wire as the length is 60 removed from the presenting - block. The length of wire being now cut off, it is swept around by the staple-forming blocks, which in connection with the anvil operate to form a staple, the ends of which are inturned, as 65 before described, by the cam projections 47

of the plate 46. As the staple thus formed is swept around to the inserting-point it passes off the end of the anvil 44, and while still under the control of the staple-forming blocks comes in contact with the spring 48, 70 which acts to steady it and retain it in the forming-blocks in position to be inserted in the traveling folded paper. Just as the staple leaves the anvil 44 the arm 60 of the staple-driving mechanism is operated through the 75 shaft 61, the arm 62, the roller 63, and the stationary cam 64 to thrust forward the staple and force it through the folded product. After the staple penetrates the folded product it meets the clenching-plate and is clenched in 80 a manner well understood.

The mechanism above described operates to insert a staple through a web which has been twice folded, once longitudinally and once transversely, or it may be a series of superposed webs thus folded. Should it be desired, however, to use the folding mechanism above described as a collecting mechanism also, one set of pins on the carrier C is thrown out and the set of pins on the 90 carrier D is made operative in a manner which is well understood in the art and need not be herein specifically described. When so adjusted, the folding mechanism will operate to collect two sheets, and it is obvious that the collected sheets will pass between the stapling-rolls only one-half as often as when the folding mechanism is not operated to collect. It is necessary, therefore, to prevent the presenting-block from presenting a 95 staple length of wire to the staple-forming mechanism every second revolution, as heretofore, and arrange it so that it will present a length of wire only once in every fourth revolution. To accomplish this, the pins 37¹⁰⁵ of the cam projections 37 are taken out, the said projections are turned on their pivots so as to fall inside the circumference of the carrier 38, and the pins are inserted in the inner line of holes so as to secure the projections 37 in place. The wire-feeding mechanism is also adjusted by throwing the gears 28 and 30 out of mesh and bringing the gears 28' and 30' into mesh. When the machine is thus 110 adjusted, the feeding operation proceeds as before, with the difference that the length of wire is fed only once in every fourth revolution of the stapling-rolls. It is obvious that by providing the carrier 38 with a sufficient 115 number of adjustable cam projections 37 and by further providing a sufficient number of change-gears to control the wire feed, the machine can be arranged to staple a great variety 120 of products.

In some forms of printing-machines now in 125 use the exigencies of space will not permit the insertion of stapling-rolls between the fold-laying rolls of the rotary folder and the rotating fly-delivery. In such cases the fold-laying rolls E and the guides F may be omit- 130

ted and the stapling-roll shafts H I and the stapling-rolls be located so as to receive the folded product directly from the rotary carrier C. Such a construction is shown in Fig.

5 12. In this construction the stapling-rolls 40, 41, 70, and 71 receive the folded product directly from the tucking-blades c of the rotary carrier C and have the function not only of the stapling-rolls, but also of fold-laying 10 rolls. Additional fold-laying rolls may also be mounted on the shafts H and I, if desired.

15 It is obvious that the mechanical details of the machine which has been described as embodying this invention may be varied widely, and many such variations in construction will suggest themselves to skilled mechanics. It is to be understood, therefore, that the invention is not limited to the particular details set forth in this specification, but that it is 20 generic in its nature and includes such variations and changes in mechanical details as fall within its spirit and its scope.

What I claim is—

25 1. The combination with a constantly-operating staple forming and inserting mechanism, of a presenting mechanism operating to deliver the wire to the forming and inserting mechanism, means for varying the operation of the presenting mechanism so that it will 30 act after a predetermined number of operations of the staple forming and inserting mechanism, wire-feeding devices, and means for varying the operation of the feeding devices so that they may act in harmony with 35 the presenting mechanism, substantially as described.

40 2. The combination with a rotary staple forming and inserting mechanism, of a presenting mechanism operating to deliver the 45 wire to the forming and inserting mechanism, means for varying the operation of the presenting mechanism so that it will act after a predetermined number of operations of the staple forming and inserting mechanism, wire-feeding devices, and means for varying 50 the operation of the feeding devices so that they may act in harmony with the presenting mechanism, substantially as described.

55 3. The combination with a rotary staple forming and inserting mechanism, of a movable presenting mechanism operating to deliver the wire to the forming and inserting mechanism, and wire-feeding devices, substantially as described.

60 4. The combination with a rotating staple forming and inserting mechanism, of a presenting mechanism operating to deliver the wire to the forming and inserting mechanism, means for rocking the presenting mechanism into and out of the path of the staple forming and inserting mechanism, and wire-feeding devices, substantially as described.

65 5. The combination with a rotating staple forming and inserting mechanism, of a pre-

senting mechanism operating to deliver the 65 wire to the forming and inserting mechanism, means for moving said presenting mechanism into position to cause it to deliver a wire length to the forming and inserting mechanism, and devices to cause the presenting mech- 70 anism to operate after a predetermined number of rotations of the staple forming and inserting mechanism, substantially as described.

75 6. The combination with a rotating staple forming and inserting mechanism, of a pre- 80 senting mechanism operating to deliver the wire to the forming and inserting mechanism, and adjustable devices to cause the presenting mechanism to operate after a predetermined number of rotations of the staple forming and inserting mechanism, substantially as de- 85 scribed.

90 7. The combination with a rotating staple forming and inserting mechanism, of a piv- 95 oted presenting mechanism operating to de- liver the wire to the forming and inserting mechanism, and means for rocking the pre- 100 senting mechanism into and out of the path of the staple forming and inserting mechanism, substantially as described.

105 8. The combination with a rotating staple forming and inserting mechanism, of a piv- 110 oted presenting mechanism operating to de- liver the wire to the forming and inserting mechanism, and adjustable means for rocking the presenting mechanism into and out of the path of the staple forming and inserting mech- 115 anism, substantially as described.

120 9. The combination with a rotating staple forming and inserting mechanism, of a piv- 125 oted presenting mechanism operating to de- liver the wire to the forming and inserting mechanism, adjustable means for rocking the presenting mechanism into and out of the path of the staple forming and inserting mech- 130 anism, and wire-feeding devices, substantially as described.

135 10. The combination with a constantly-oper- 140 ating staple-forming mechanism, of a piv- 145 oted presenting mechanism operating to de- liver the wire to the forming and inserting mechanism, adjustable means for controlling the operation of the presenting mechanism, wire-feeding devices, and means for varying 150 the operation of the feeding devices so that they will act in harmony with the presenting mechanism, substantially as described.

155 11. The combination with a staple-forming mechanism, of a grooved presenting-block, and means for moving the block into and out 160 of the path of the staple-forming mechanism, substantially as described.

165 12. The combination with a rotating staple-forming mechanism, of a grooved presenting-block, and means for moving the block into and out of the path of the staple-forming mechanism, substantially as described.

170 13. The combination with a rotating staple-

forming mechanism, of a pivoted presenting-block provided with means for receiving and holding the wire, and means for rocking said block into and out of the path of the staple-forming mechanism, substantially as described.

14. The combination with a rotating staple-forming mechanism, of a pivoted presenting-block provided with means for receiving and holding the wire, and adjustable means for rocking said block into and out of the path of the staple-forming mechanism, substantially as described.

15. The combination with a staple-forming mechanism having means for receiving a length of wire and carrying it onward to form it into a staple, of a pivoted presenting-block provided with means for receiving and holding the wire, adjustable means for controlling the operation of the presenting-block, wire-feeding devices, and means for varying the operation of the wire-feeding devices so that they will act in harmony with the presenting-block, substantially as described.

25 16. The combination with a rotating staple-forming mechanism embodying a pair of spaced forming-blocks, of a presenting-block operating to deliver a length of wire to the forming-blocks, and means for moving the presenting-block into and out of the space between the forming-blocks, substantially as described.

35 17. The combination with a rotating staple-forming mechanism embodying a pair of spaced forming-blocks, of a pivoted presenting-block operating to deliver a length of wire to the forming-blocks, and means for rocking the presenting-block into and out of the space between the forming-blocks, substantially as described.

45 18. The combination with a rotating staple-forming mechanism embodying a pair of spaced forming-blocks, of a pivoted presenting-block operating to deliver a length of wire to the forming-blocks, and adjustable means for rocking the presenting-block into and out of the space between the forming-blocks, substantially as described.

50 19. The combination with a rotating staple-forming mechanism embodying a pair of spaced forming-blocks, of a pivoted presenting-block operating to deliver a length of wire to the forming-blocks, adjustable means for rocking the presenting-block into and out of the space between the forming-blocks, wire-feeding devices, and means for varying the operation of the wire-feeding devices so that they will act in harmony with the presenting-block, substantially as described.

60 20. The combination with a staple-forming mechanism of a movable presenting-block, and a wire-guide having a movement corresponding with the movement of the presenting-block, substantially as described.

21. The combination with a rotating staple-forming mechanism embodying a pair of spaced forming-blocks, of a presenting-block movable into and out of the space between the forming-blocks, and a wire-guide moving with the presenting-block, substantially as described.

22. The combination with a rotating staple-forming mechanism embodying a pair of spaced forming-blocks, of a pivoted presenting-block, means for rocking the block into and out of the space between the forming-blocks, and a wire-guide secured to and moving with the presenting-block, substantially as described.

23. The combination with a rotating stapling mechanism embodying a pair of forming-blocks spaced apart, of a pivoted presenting-block, a wire-guide secured to and moving with the presenting-block, adjustable devices for rocking the presenting-block and guide, wire-feeding rolls, and means for varying the operation of the feeding-rolls so that they will act in harmony with the presenting-block, substantially as described.

24. The combination with a movable presenting-block, of a pair of wire-feeding rolls, a perforated wire-guide between the feeding-rolls and the presenting-block, said guide moving with the block, and the mouth of the perforation which receives the wire from the rolls being flared, substantially as described.

25. The combination with a rotary staple-forming mechanism, of a pivoted presenting-block, a rock-arm connected to and operating the block, and a cam-disk for operating the rock-arm, substantially as described.

26. The combination with a rotary staple-forming mechanism, of a pivoted presenting-block, a rock-arm connected to and operating the block, a cam-disk for operating the rock-arm, and a spring for holding the rock-arm in contact with the cam-disk, substantially as described.

27. The combination with a rotary staple-forming mechanism, of a pivoted presenting-block, a rock-arm connected to and operating the block, a cam-disk for operating the rock-arm having adjustable cam projections, and a spring for holding the rock-arm in contact with the cam-disk, substantially as described.

28. The combination with a rotary staple-forming mechanism, of a pivoted presenting-block, a rock-arm connected to and operating the block, a cam-disk having adjustable cam projections for operating the rock-arm, a spring for holding the rock-arm in contact with the cam-disk, wire-feeding devices, and means for varying the operation of the wire-feeding devices so as to cause them to act in harmony with the adjustable cam described, substantially as described.

29. The combination with the delivery of a printing-machine, of means whereby it is

caused to deliver different products, a constantly-running stapling mechanism for inserting staples in said products, said mechanism including continuously-operating wire-feeding devices and a presenting mechanism, and means whereby the number of staples inserted by the stapling mechanism may be varied according to the product to be stapled, substantially as described.

30. The combination with the delivery of a printing-machine having means whereby it may be used either as collecting or non-collecting delivery, of a constantly-rotating staple-forming mechanism, said mechanism including continuously-operating wire-feeding devices and a presenting mechanism, and means whereby the staple-forming mechanism may be caused to form and insert a staple once in a predetermined number of rotations of the staple-forming mechanism, substantially as described.

31. The combination with a staple forming and inserting mechanism running at a constant speed, of continuously-operating means for supplying wire thereto, means for causing said supplying means to operate at varying speeds, a presenting mechanism, and means for varying its operation in accordance with the speed of the supplying means, substantially as described.

32. The combination with the delivery of a printing-machine, of means whereby it may be caused to deliver different products, a constantly-running staple forming and inserting mechanism, continuously-operating wire-feeding mechanism, a presenting mechanism, and means whereby the operation of the wire-feeding and presenting mechanisms may be varied according to the products delivered by the delivery mechanism, substantially as described.

33. The combination with the delivery mechanism of a printing-machine, means whereby it may be caused to deliver different products, a constantly-running staple forming and inserting mechanism, a presenting mechanism operating to deliver the wire to the stapling mechanism, wire-feeding devices, and means for varying the operation of the presenting mechanism and of the wire-feeding devices so that the wire shall be fed and presented to the staple forming and inserting mechanism according to the products delivered by the delivery mechanism, substantially as described.

34. The combination with a printing-machine, of a carrier having a tucking-blade, and a pair of stapling-rolls between which the product is tucked by the blade of the carrier, said stapling-rolls operating both to fold and staple the product, substantially as described.

35. The combination with a printing-machine, of a carrier having a tucking-blade, a pair of stapling-rolls between which the prod-

uct is tucked by the blade of the carrier, said 65 stapling-rolls operating both to fold and staple the product, and means for delivering the product folded and stapled by the stapling-rolls, substantially as described.

36. The combination with a printing-machine, of a rotating carrier having a tucking-blade, a pair of stapling-rolls between which the product is tucked by the blade of the carrier, said stapling-rolls operating to both fold and staple the product, and a rotating fly-delivery 70 operating to receive the folded and stapled product of the printing-machine, substantially as described.

37. The combination with a pair of rotating staple-forming blocks, of a staple-driver located 75 between the blocks, means for operating the driver at the proper time to insert the staple, a horn located between the blocks, and said horn being provided with a spring extending beyond its end which serves to steady 80 the staple at the beginning of the driving operation, substantially as described.

38. The combination with a shaft, of a pair 85 of rotating staple-forming blocks, a driver located between the blocks, a lever connected to the driver, a rock-shaft for operating the lever carried on the shaft on which the blocks are mounted, and a stationary cam serving to operate the rock-shaft, substantially as described.

39. The combination with a rotating shaft, 90 of a pair of rolls carried thereby and suitably spaced apart, a pair of staple-forming blocks carried in the space between the rolls, a staple-driver located between and guided by said 95 blocks, a lever for operating the driver, a rock-shaft mounted in one of the rolls, an operating-arm on the shaft, and a stationary cam co-operating with the arm, substantially as described.

40. The combination with a staple-forming mechanism, of a pair of wire-feeding rolls, a pair of intergeared shafts for operating the rolls, a pinion on one of the shafts, a shaft carrying a pinion meshing with the pinion on 100 the operating-shaft and provided with a gear, a continuously-driven shaft carrying a pair of sliding gears of different diameters, and means whereby either of said gears may be caused to operate the shaft carrying the pinion and gear, substantially as described.

41. In a stapling-delivery for printing-machines, the combination with a rotating carrier having tucking-blades, pins and one member of a cutting mechanism, of a cylinder co-operating therewith and having pins and the other member of the cutting mechanism, a shaft carrying a rotating fly, a train of gears between the shaft of the rotating carrier and the fly-shaft, a pair of stapling-rolls located 110 between the carrier and the fly, a train of gears between the fly-shaft and the stapling-rolls, a wire-feeding mechanism, including a

pair of rolls, shafts on which the rolls are mounted, stationary bearings for the shaft and means including change-gears between the wire-feeding mechanism and the train 5 leading from the fly-shaft to the stapling mechanism for operating the wire-feeding mechanism, whereby the carrier, the fly-shaft and the stapling-rolls are given a constant rotation and the speed of the feeding mechanism may be varied according as the cylinders

are used as collecting or non-collecting cylinders, substantially as described.

In testimony whereof I have hereunto set my hand in the presence of two subscribing witnesses.

LUTHER C. CROWELL.
